APPARATUS FOR GRADING LEATHER, ETC.

Evan George Wilson, Blundellsands, near Liverpool, England

Application May 23, 1935, Serial No. 22,945
In Great Britain June 2, 1934

9 Claims. (Cl. 33—148)

This invention relates to the grading or selection of leather and other suitable materials or substances in sheet form (all hereinafter for convenience, referred to as "leather"), and has for its object to provide apparatus whereby such sheets which are of varying thicknesses throughout, may be measured and the thicknesses of each individual sheet indicated or charted at convenient steps or stages of the measuring, so as to enable or permit, in a ready and convenient manner, selection of sheets most suitable for any particular use or intended purpose. Moreover, the apparatus is capable of large output capacity and operation by unskilled or semi-skilled labor, and is simple and accessible in construction and of neat and compact design.

Grading or selecting apparatus, according to my invention, is characterized in that it includes "feeler" elements adapted to operate upon the leather and a graduated or otherwise suitably marked chart or scale, or the like; and means between each feeler element and said chart or scale, or the like, for automatically selecting and individually operating a series of indicator strips, fingers, markers, or the like, in response to the movements of respective feeler elements and in such fashion that said markers, or the like, appear on or register with or/and mark the chart or scale, or the like, and—by observation of the various readings shown by the markers—provide or/and record visual indication of the thicknesses of a sheet of material acted upon by the apparatus. Thus information as to the suitability or otherwise of a sheet for a particular purpose may readily be ascertained by mere inspection of the chart or scale, or the like. The markers themselves may be returned to their original positions after operation by hand or by suitable delay control means.

In one arrangement under my invention, there are provided feeler wheels or discs adapted to be yieldably and independently maintained in contact with the surface of a sheet of leather immediately above feeding rollers or spindles protruding above a table, or the like; a bar or equivalent selector located above each feeler wheel and adapted to be reciprocated within predetermined limits in a horizontal plane—and in response to the vertical displacement of said feeler wheel—by mechanism operatively connecting the latter with said selector; means located below the selector and adapted to reciprocate the same in a vertical plane at suitable predetermined intervals; an actuating element carried by said selector; a scale or chart provided with

a series of horizontally spaced graduations, mounted in any convenient position with respect to said actuating element; a series of horizontally spaced indicator strips, fingers, markers, or the like, provided with vertically spaced graduations adapted to move in register with said horizontally spaced scale readings of the chart; and mechanical means, such, for example, as spring pawl and rack devices associated with pivotal link frame or lever structures, whereby individual indicator strips may be longitudinally projected by step-motion over or in front of said chart or scale through upward projection of said actuating element in response to vertical displacements of the selector which carries the latter. Preferably, a separate indicator strip or marker is provided to co-operate with each horizontally spaced graduation of the scale or chart, and individual mechanical means or devices are associated with each strip or marker, such devices being conveniently arranged side-by-side above said actuating element of the selector, so that any strip or marker may be operated by said actuating element (which, of course, reciprocates in a horizontal plane below said mechanical actuating devices conjointly with the selector) according to the position of said actuating element at the moment of a vertical displacement of the selector.

A suitable counter, or the like, is preferably associated with the scale or chart and which counter is adapted to indicate the total number of step-motions or registrations imparted to individual strips or markers.

I will further describe my invention with the aid of the accompanying sheets of explanatory drawings which illustrate, by way of example only, one mode of embodying same.

In said drawings:—

Fig. 1 is a side sectional elevation, and Fig. 2 a front view with parts broken away, of apparatus constructed in accordance with the invention.

Fig. 3 is an enlarged side elevation of indicating mechanism detached from the apparatus, and Fig. 4 is a plan view of Fig. 3.

Fig. 5 is a further enlarged side elevation of a portion of the mechanism illustrated in Fig. 3, and Fig. 6 is a front view of same with a cover plate and indicator strips removed.

Fig. 7 is a cross-sectional elevation (drawn to a scale similar to that of Figs. 5 and 6) taken as on the line A—A Fig. 3 and viewed in the direction indicated by the arrow.

Fig. 8 is a rear view, with parts broken away, illustrating the ratchet drum and mechanism embodied in Fig. 5 for the purpose of operating

the adding or totalizing device of the recording apparatus.

Fig. 9 is an enlarged detail elevation of an actuating arm mounted upon its selector bar, and Fig. 10 is a plan view illustrating in diagrammatic form the cam roller arrangement for operating the actuating arms.

In the several views like characters of reference denote like or equivalent parts wherever they occur.

Referring to the drawings, 1 designates feeler wheels or discs rotatably mounted on lateral arm 2 of bell crank levers 2, 3 which are fulcrumed upon a common shaft 4 having its opposed ends affixed to side members 5 of the apparatus. The longer upstanding arms 3 of levers 2, 3 are fitted at their upper ends with adjusting means comprising springs 6 and floating sleeves 7 whereto are connected ends of horizontal link rods 8 the 20 opposite ends whereof are pivotally secured at 9 to vertically positioned links 10, which latter are also pivotally mounted upon and suspended from a horizontal shaft 11 disposed between upper portions of side members 5. The lower ends of 25 said links 10 are pivotally articulated at 12 to lateral coupling rods 13, the other ends whereof being similarly connected at 14 to reciprocatory selector bars 15 each of which is adapted to move horizontally between spaced supporting and guide rollers 16 disposed upon spaced rods 17 secured to side members 5.

Said feeler wheels 1 are yieldably and independently maintained in contact with the surface of a sheet of leather passing below same under the pressure of helical springs 18 disposed around upper portions of guiding rods 19 which are slidably located in passages formed in blocks 20 affixed to the framework of the apparatus; said rods 19 being pivotally connected at 21 with 30 the outer free ends of lateral arms 2 of bell crank levers 2, 3.

Positioned immediately below each feeler wheel 1 is a feeding roller 22 mounted upon, and adapted to rotate in conjunction with, a horizontally disposed driven shaft 23 which is located in bearings provided for its reception in side members 5: said rollers 22 protrude above the surface of a table 24.

It will thus be apparent that the feeler wheels 1 will be individually and vertically displaced in response to varying thicknesses of a sheet passing between same and feeding rollers 22, and, by oscillating their respective carrier levers 2, 3, impart, through the medium of their associated connecting links 8, 10 and 13, corresponding reciprocatory motion to the horizontally movable selector bars 15.

Disposed below each selector bar 15 are pairs of oppositely rotated discs 25 (see more particularly Figs. 1 and 10) fixed to shafts 26 mounted in bearings provided in side members 5. Each pair of discs 25 are provided with crank pins 27 whereon are fitted rollers 28 which are adapted to simultaneously bear against and act upon the underside of their particular selector bar 15 and so impart vertical reciprocatory movement to same in parallel planes.

Each selector bar 15 is successively raised by its associated pair of discs 25 with rollers 28, because in their rotative order each particular pair of crank pins 27 are off-set for such purpose—the arrangement being as shown in Fig. 10—so that each selector bar 15 is vertically displaced in turn during a complete revolution of shafts 26 which, through a train of toothed wheels

29, are caused to rotate (being driven by any suitable power source) in opposite direction to each other, and lateral displacement of the selector bars 15 by the movement of the rollers 28 when raising their particular selector bar 15 is prevented. Upon one of said shafts 26—i. e. the driving shaft—there is secured a sprocket wheel 30—see Fig. 2—around which is disposed a chain 31 adapted to drive a sprocket wheel 32 secured to driven shaft 23 which rotates the leather feeding rollers 22.

Carried by each selector bar 15, and preferably in an intermediate position thereon, is an actuating or striker element 33 consisting of a small bevel wheel or roller 34 mounted at the upper 15 end of an arm 35 which is attached at its lower end to a horizontal carrier 36 mounted upon springs 37 disposed about vertical rods 38, and to the upper portions of rods 38 there are secured ends of lateral springs 39 which are connected 20 to opposed sides of arm 35: thus arm 35 of said actuating element 33 is rendered flexible and capable of yielding both laterally and vertically to the requisite extent: in lieu of said roller 34 the upper extremity of arm 35 may be suitably 25 pointed or chamfered.

Rollers 34 of actuating elements 33 are adapted to move under—prior to engaging with—any one of a series of parallel and horizontally arranged guiding rails or bars 40 which are disposed immediately above said elements 33, the side components of said bars 40 being chamfered at their lower longitudinal edges 40^a in order to receive the correspondingly shaped peripheries of the rollers 34 when engaging therewith: said 35 side components are spaced apart and secured together by means of distance pieces 40^b and rivets, as illustrated more particularly in Fig. 9.

Coinciding with said distance pieces 40^b and positioned between each built-up bar 40, 40^a, 40^b, 40^c are a series of spacing and guiding plates 41 which are fixed upon common cross rods 41^a and formed with central recesses 41^b in horizontal alignment with each other and also with rollers 34 of actuating arms 35; said recesses 41^b having upper inclined knife edges 41^c in order to deflect the rollers 34 onto the chamfered edges 40^a of the side components of bars 40, so preventing the rollers from riding along said knife edges 41^c if tending to do so.

The ends of bars 40 are individually and pivotally connected by means of pins 42 to the lower portions of inclined levers 43, 44 which are centrally swivelled about respective common axes 45, 45^a, the upper ends of said levers 43, 44 being independently and pivotally secured by means of pins 46 to opposed ends of connecting links 47 which ensure correct parallel movements of bars 40 in a vertical plane upon actuation of the individual pivotal link frame or lever structures which pivot about their common axes 45, 45^a by upward movement of the actuating elements 33 when engaged by the rollers 34 thereof: lower extensions 43^a of levers 43 are located within a common channel 48^a formed in a bar 48 transversely secured between side members 49 of a frame 50 provided to house the series of link structures. Attached to said extensions 43^a of levers 43 are ends of coiled springs 51, opposed ends whereof are secured to cross bar 48 in a 70 manner that ensures the return of bars 40 when operated after the descent of actuating elements 33.

Disposed about the common axis 45 and fixedly secured to levers 43 are base portions of arm 75

members 52 which extend upwardly at right angles from said levers 43 and carry at their upper extremities a series of pivotal pawls 53 and—between these and levers 43—a further series of 5 pivotal pawls 53a. The pairs of pawls 53, 53a have their lower arms 54, 54a coupled together by coiled springs 55—see Fig. 5—which normally and individually maintain said arms 54 of pawls 53 against a transversely positioned and pivotally mounted common stop bar 56 and arms 54a of pawls 53a in abutment with a similar stop bar 57, said stop bars 56, 57 being pivotally connected by means of crank arms 58 to a link 59 positioned adjacent a side 49 of frame 50: said 15 link structure 58, 59 is operated by a slidable handle 60 secured to an external portion of the link structure pivot 61.

Said handle 60 when operated moves stop bars 56 and 57 away from each other, and another 20 stop bar 62 attached to link 59 by means of crank arm 62a is positioned against the lower ends of arms 63 of holding pawls 64 pivotally mounted upon a common rod 65 transversely secured to sides 49 of frame 50, said arms 63 being individually held in abutment with stop bar 62 by extension springs 66 attached thereto and to a common slotted bar member 66a secured to sides 49 of frame 50: the slots 66b of bar 66a slidably house and locate arm members 52. Stop bars 56, 30 62 in their operative movement against arms 54, 63 move pawls 53, 64 out of normal engagement with the toothed rear portions of a plurality of indicator strips or markers 67 in juxtaposition with each other and independently and slidably 35 mounted within a carrier frame 68 secured to sides 49 of frame 59. Said indicator strips 67, being thus released, slide down by gravity when resetting, so that their lower end portions come to rest upon the common bed portion of carrier 40 frame 68. The strips 67 bear upon their upper surfaces 69 a plurality of vertically spaced characters or markings (not shown) which are thus carried behind a scale or chart constituted by an index plate 70 adjacent a transverse slot or 45 window 71 formed in front plate 68a of frame 68. Said index plate 70 also bears horizontally spaced characters or markings 70a each of which registers with the series of vertically spaced characters carried by indicator strip 67. An additional 50 or supplementary index plate 70b—similar to index plate 70a—and transverse window 71a may be provided as illustrated in Fig. 4 to register with the projecting portions of the indicator strips 67 so that by comparing the various projecting portions of the strips 67 with the registering markings of the index plate 70b an indication of the proportionate thicknesses of a sheet is available.

The scales 70 and 70b are both graduated in 60 "irons", horizontally, so that each of the graduations which shows the various thicknesses of the leather registers with one of the indicator strips 67. Each of these strips 67 is numerically graduated and is projected longitudinally in register 65 with one of the horizontal thickness graduations 70a of the indicator 70. For instance, if one strip 67 has been actuated five times the number 5 carried on this strip will appear in window 71 in register with a thickness graduation 70a of 70 indicator 70, thus an observer will see that five points on the leather at which gauging has been effected are this thickness. In this manner all the strips 67 are actuated in accordance with the varying thicknesses of the leather.

75 The strips 67, thus actuated, will also appear,

within the window 71a, projected at various heights beyond the supplementary index plate 70b to provide a visual indication—in a graphical fashion—of the proportionate thicknesses of the hide operated upon by the machine.

Simultaneously with the release of pawls 53, 64 pawls 53a disengage from the teeth of a common ratchet drum 72 secured to a shaft 73 transversely mounted between sides 49 of frame 50. One end of shaft 73 projects through a side 49 and is 10 adapted to operate a counter 74—in the form of a disc having spaced circumferential markings 74a—disposed adjacent the face of said side 49. The counter is housed within a casing or cover 74b provided with a window or opening 74c.

The opposite end of shaft 73 extends through its adjacent side 49 of frame 50, and secured thereon is a winding pulley or drum 75 around which there is coiled a portion of a rope or chain 76, to the free end of which there is fixed a weight (not 20 shown) which returns the counter through the medium of gear wheels 73a, 73b to its normal zero reading in the resetting operation.

Drum 75 is provided with a ratchet wheel 77 integral therewith and which is normally engaged by catch 78 of a holding lever 79 pivotally attached at its lower end to a side 49 of frame 50 by means of a coiled spring 80, so that when link 59 is moved upward by crank arms 58 an extension 59a strikes holding lever 79 and causes catch 30 78 to disengage from ratchet wheel 77 to free ratchet drum 75 for re-setting as before described: by this arrangement drum 72, shaft 73 and counter 74 can only be rotated by step-motion.

In operation, as a sheet of material is passed over feeding rollers 22 of table 24, feeler wheels 1, being independently maintained in contact with the adjacent surface of the moving sheet by means of springs 18, will individually move up 40 and down in accordance with variations or unevenness in the thickness of the sheet, to cause oscillation of their respective bell crank carriers 2, 3, which, in turn, and through the medium of the coupling links 8, 10 and 13, horizontally reciprocate—in response to the vertical displacements of the feelers 1—the selector bars 15 and their actuating arms 35. Simultaneously, opposed pairs of the crank rollers 28 of discs 25 intermittently and successively engage with respective selector bars 15 consequent on the off-setting of respective pairs of crank rollers 28, to cause, by such engagement, intermittent vertical displacements of bars 15 and so the actuating arms 35 mounted upon same. Consequent on each upward 50 displacement of individual actuating arms 35, the particular bar 40 of the vertical frame or lever structure in vertical alignment with the actuating arm 35 now operating is engaged by the latter and raised and swivelled forward within adjacent spacing plates 41 about its axes 45, 45a accordingly, so imparting—through the medium of its associated parts and pawl 53—limited step motion to the particular toothed indicator strip 67 engaged by said pawl 53 consequent on abutment of extension 43a of lever 43 against a side of channel 43a, said strip being held in such position by its associated pawl 64. In this manner, each actuating arm 35 is moved by its selector bar 15 (during a complete revolution of driving 60 shaft 26) underneath and horizontally across the series of bars 40 in order to automatically select and operate any one of same, according to the vertical displacements of individual feeler wheels 1, as a sheet of leather is being passed under 75

same and consequent on the varying thickness thereof.

The indicator strips 67, thus moved upwardly in carrier frame 68, appear with the characters 5 they bear for observation through transverse window or slot 71, each character being in register with a horizontal graduation 70^a of index plate 70. At the same time, each step-by-step movement of each indicator strip 67 has been 10 imparted to counter 74 (consequent on pawls 53^a imparting step-motion to ratchet drum 72) which shows a reading through casing opening 74^c to indicate the total number of registrations or 15 movements as they are made by the series of operated indicator strips 67.

On noting the readings of each particular indicator strip 67 in conjunction with the registering 20 graduations 70^a of the index plate 70, an observer will be aware of the number of points 25 at which gauging has been effected and the thicknesses of the leather at these points, as each step movement of individual strips 67 constitutes one point of gauging and the registering mark of the index plate 70 indicates the thickness of the 25 leather at such point.

The indicating strips 67 and counter 74 are re-set to zero positions by means of handle 60 as hereinbefore described.

It will be obvious that any other suitable 30 mechanism may be utilized between the actuating elements 33 and the indicating strips or markers 67 and counter 74, to attain the object of my invention; also, with the aid of some such modified mechanism the indicator strips may be 35 arranged to operate in any desired angular position from vertical to horizontal. Further, whilst, for convenience of description, my invention has been described with reference to the employment of 40 a plurality of feeler wheels and parts associated therewith, I desire my claims to include apparatus adapted to the use of a single feeler wheel only.

What I claim as my invention and desire to 45 secure by Letters Patent is:—

1. Apparatus for use in the grading or selection of leather according to thickness, characterized in that it includes "feeler" elements adapted to operate upon the leather in such manner as 50 to rise and fall with same due to varying thicknesses, and a graduated indicator; a series of indicator strips adapted to register with said indicator; and means, movable to positions to actuate any of the indicator strips, disposed between each feeler element and said indicator for 55 automatically selecting and individually operating said indicator strips only when the particular thickness for that strip causes said means to be brought into corresponding position in response 60 to the movements of respective feeler elements and in such fashion that said indicator strips register with the indicator to provide visual indication of the thicknesses of a sheet acted upon by the apparatus.

2. Apparatus for use in the grading or selection of leather according to thickness, comprising feeler wheels adapted to be yieldably and independently maintained in contact with the surface of a sheet of leather immediately above feeding 70 rollers; a selector bar located above each feeler wheel and adapted to be reciprocated within predetermined limits in a horizontal plane and in response to the vertical displacement of said feeler wheel by mechanism operatively connecting the latter with said selector; means located

below the selector and adapted to reciprocate the same in a vertical plane at suitable predetermined intervals; an actuating element carried by said selector; an indicator provided with a series of horizontally spaced graduations; a series of horizontally spaced indicator strips provided with vertically spaced graduations, adapted to move in register with said horizontally spaced readings of the indicator; and mechanical means whereby individual indicator strips can be longitudinally projected by step-motion to register with said indicator only when the particular thickness for that strip passes beneath the feeler elements and through upward projection of said actuating element in response to vertical displacement of the 15 selector which carries the latter.

3. Apparatus for use in the grading or selection of leather according to thickness as claimed in the preceding claim 2, in which a separate indicator strip is provided to co-operate with each 20 horizontally spaced graduation of the indicator, and individual mechanical devices are associated with each indicator strip, such devices being conveniently arranged side-by-side above said actuating element of the selector so that any indicator strip may be operated by said actuating element only when the particular thickness for that strip passes beneath the feelers and according to the position of said actuating element at the moment of a vertical displacement of the 30 selector.

4. Apparatus for use in the grading or selection of leather according to thickness as claimed in the preceding claim 2, in which a separate indicator strip is provided to co-operate with each 35 horizontally spaced graduation of the indicator, and individual mechanical devices are associated with each indicator strip, such devices being conveniently arranged side-by-side above said actuating element of the selector so that any indicator strip may be operated by said actuating element only when the particular thickness for that strip passes beneath the feelers and according to the position of said actuating element at the moment of a vertical displacement of the selector; said 40 mechanical means actuating individual indicator strips, comprising a series of spring pawl and rack devices associated with pivotal lever frame structures, whereby individual indicator strips may be longitudinally projected by step-motion to register with the readings of the indicator.

5. Apparatus for use in the grading or selection of leather according to thickness, as claimed in the preceding claim 2; in which said actuating 55 element carried by the selector includes an arm attached at its lower end to a horizontal carrier having connection through springs with the top of the selector and also lateral springs connecting opposed sides of the arm with upper ends of rods 60 which guide said carrier, for the purpose specified.

6. Apparatus for use in the grading or selection of leather according to thickness, as claimed in the preceding claim 2, in which the selector bars are adapted to be reciprocated in vertical planes 65 by means of spaced pairs of discs carrying crank pin rollers.

7. Apparatus for use in the grading or selection of leather according to thickness, as claimed in the preceding claim 2, in which the selector bars 70 are adapted to be reciprocated in vertical planes by means of spaced pairs of discs carrying crank pin rollers, respective pairs of said crank pin rollers being off-set, for the purpose specified.

8. Apparatus for use in the grading or selection 75

of leather according to thickness, as claimed in the preceding claim 1, in which a counter is arranged to indicate the total number of step-motions or registrations imparted to individual indicator strips by an operative connection therewith.

5. Apparatus for use in the grading or selec-

tion of leather according to thickness as claimed in the preceding claim 1, in which an additional indicator is provided adjacent the indicator strips in order to co-operate with the projecting portions thereof, for the purpose specified.

5

EVAN GEORGE WILSON.
